New York, N.Y., a corporation of Delaware
Filed Sept. 1, 1966, Ser. No. 576,656
4 Claims. (Cl. 239—543)

ABSTRACT OF THE DISCLOSURE

Actuator for dispensing fluid from an aerosol container in a plurality of skew (non-parallel, non-intersecting) streams.

The present invention relates to actuators for dispensing fluids from a container package holding the same, including pressurized and pump-type containers. In particular, the invention relates to actuators producing a mechanical break-up of the fluid stream being dispensed.

Numerous, nozzle or spray-head devices are known in the prior art for producing aerosols, i.e. finely divided liquid or solid particles suspended in a gas, commonly air. Devices exist in the prior art for effecting solid-liquid or liquid-liquid mixing in those cases where solids are to be dispensed using a liquefied gaseous propellant, or where two or more liquids separately stored in a container package are to be mixed and/or mechanically subdivided at the time they are dispensed in the form of an aerosol. In these prior art devices, mixing and/or subdivision is commonly effected within the nozzle actuator device by passing the material to be ejected as an aerosol through tortuous passages or by impinging it on baffle plates, for example. Prior art devices of this type, particularly when employed to dispense finely divided powders as an aerosol, are subjected to the serious disadvantage that the passages, baffles, mixing chambers, etc. within the actuator easily become clogged with the solids to be dispensed. The very same steps taken in the prior art to mix and/or subdivide the materials being dispensed render the prior art actuators vulnerable to misfunctioning.

According to the present invention, an actuator, nozzle device, or spray head suitable for use on pressurized and pump-type containers for dispensing fluids, including fluidized solids, in the form of an aerosol is disclosed in which mixing of a plurality of fluid streams is effected externally to the actuator device. The novel actuator eliminates the need for internally complex dispensing devices, thus facilitating the manufacture of the actuator, and—by elimination of the tortuous passages or baffle plates common in the prior art—renders the actuator of the invention more reliable and less subject to clogging and other malfunction.

The objects of the present invention are accomplished by the use of an actuator having a plurality of skew orifices through which fluid streams are ejected in a fashion such that the cross-sections of the streams are tangential at a point exterior to the actuator. By "fluid stream" as employed in the specification and claims is to be understood a gaseous or liquid stream, or a mixed stream of gases and liquids, in which solid particles may also be suspended.

A better understanding of the present invention and of its many advantages will be had by referring to the accompanying drawings in which:

FIGURE 1 is a perspective view of an actuator according to the invention in which the configuration of the interior cavity and the position of the orifices have been indicated by broken lines;

2

FIG. 2 is a side elevation, in section, taken along lines 2—2 of FIG. 1;

FIG. 3 is a rear elevation, in section, taken along lines 3—3 of FIG. 2 showing interior portions of that part of

5 the actuator in which the exit orifices are located; and
FIG. 4 is a bottom view of the actuator taken along lines 4—4 of FIG. 2.

The figures show actuator 11, such as of plastic, affixed to valve stem 12 of a conventional pressurized or pump-type container for dispensing a fluid stream in the form of an aerosol. Actuator 11 comprises internal cavity 13 respectively in communication with first exit orifice 14 and second exit orifice 15 through first passage 16 and first interior orifice 17 and second passage 18 and second interior orifice 19. Actuator 11, suitably formed by molding or the like, is provided with shoulders 20 which limit the penetration of valve stem 12 into the actuator.

Passages 16 and 18 are so positioned within actuator 11 that their axes are skew lines, i.e. non-parallel non-intersecting lines. Passages 16 and 18 are further so positioned that the fluid streams, generally conical in cross-section, respectively emanating from first and second exit orifices 14 and 15 meet substantially tangentially at a point exterior to actuator 11.

25 The point at which the cross-sections of these two streams will be substantially tangential is dependent on the orientation of skew passages 16 and 18 to each other, on the diameter of the passages and of exit orifices 14 and 15, and also is dependent to some extent on the nature of the fluid being ejected and the conditions of pressure and temperature under which it is ejected. Each of these factors will have some influence on the size, shape, and orientation of the generally conical cross-section of the gas stream emanating from each exit orifice 30 of the actuator. However, it is not critical to the present invention that the point of substantial tangency be at any specific critical distance from the actuator head, providing that the point of substantial tangency is between actuator 11 and the point of application at which the fluid streams being ejected are directed.

35 At the point of tangency or substantial tangency of the ejected fluid streams, the streams interact by a process which may be characterized as "mutual entrainment" or "collision" so that a strong swirling action is imparted 40 to the streams. The resulting turbulence effects the break-up of particles or agglomerates of liquids or solids which may be present in the gas stream and promotes fine dispersion of the smaller liquid or solid particles which result.

45 When used with pump-type containers for dispensing fluids, the two fluid streams emanating from exit orifices 14 and 15 of an actuator according to the invention impinge tangentially as described, bringing about subdivision of the fluid within the streams into fine liquid particles forming a mist in the surrounding atmosphere.

50 However, the actuators of the present invention are particularly useful for dispensing solid powders in aerosol form. The extreme simplicity and smooth line of cavity 13 discourage caking or entrapment of solid particles within the cavity, as is common in actuators having interior baffle plates. Passages 16 and 18 of the novel actuator shown in the drawings and the respective interior and exit orifices of each are not tortuous, and can be made of a diameter sufficient to pass small solid agglomerates which may be present.

55 The swirling action caused by mutual entrainment or collision of the propelling gas streams carrying the powders aids in the break-up of any agglomerates therein and in dispersion of the finely divided solid as an aerosol.

What is claimed is:

1. An actuator for a container package for dispensing a fluid in aerosol form, said actuator comprising a housing having a plurality of openings therein, said openings being formed with non-parallel, non-intersecting axes so as to discharge a plurality of fluid streams meeting substantially tangentially exterior to said housing. 5
2. An actuator as in claim 1 having two such openings.
3. An actuator for dispensing a fluid in aerosol form, said actuator comprising a housing having an interior cavity, a passage in communication with said cavity for receiving fluid to be dispensed, and a plurality of passages in said housing, each passage being defined at a first end thereof by discharge orifice and being entrant on said cavity at a second end thereof, the axes of said passages being non-parallel, non-intersecting and mutually oriented to discharge fluid streams meeting substantially tangentially exterior to said housing. 10
4. An actuator as in claim 3 having two such passages. 15
